COMBINATION SERVING STAND AND
BEVERAGE DISPENSER

George W. Klenk, Eugene, Oreg.

Application August 31, 1951, Serial No. 244,570

6 Claims. (Cl. 222—108)

1

This invention relates to beverage dispensers and more particularly to a dispenser including a reservoir for storing a quantity of the beverage to be dispensed and manually operated dispensing means, and which may also include means for chilling the beverage in the reservoir.

It is among the objects of the invention to provide an improved beverage dispenser which includes separable parts and may be assembled to provide a stand for fruits, pastries or similar articles, to provide a dispenser for hot beverages in which case no chilling means is included, or a dispenser for cold beverages complete with chilling means for the beverage, and which includes, in all cases, a movable tray for drinking glasses; which maintains the beverage stored therein in a clean and uncontaminated condition, and which is simple and durable in construction, economical to manufacture, and neat and attractive in appearance.

Other objects and advantages will become apparent from a consideration of the following description and the appended claims in conjunction with the accompanying drawing wherein:

Figure 1 is a top plan view of a beverage dispenser illustrative of the invention;

Figure 2 is a side elevational view of the beverage dispenser illustrated in Figure 1;

Figure 3 is a cross sectional view on the line 3—3 of Figure 1;

Figure 4 is a cross sectional view on the line 4—4 of Figure 2; and

Figure 5 is a fragmentary elevational view with parts broken away and shown in cross section to illustrate a structural detail of the dispenser.

With continued reference to the drawing, the dispenser includes a base plate 10 of circular shape having an upstanding marginal rim or flange 11 and a stem 12 having a substantially cylindrical intermediate portion 13 and diametrically enlarged top and bottom end portions 14 and 15 with the end portion 15 disposed on the base plate 10 centrally of the base plate, so that the longitudinal center line of the stem is substantially perpendicular to the base plate. The stem may be formed separately from or integrally with the base plate, as may be desired, and the enlarged bottom end 15 of the stem is materially smaller than the diameter of the base plate, leaving an annular portion of the base plate disposed around the bottom end of the stem. A drinking glass carrier 16 of annular shape is rotatably mounted on the base plate 10 surrounding the bottom end portion 15 of the stem 12 and is provided with a circular series of

2

spaced apart recesses 17 for receiving drinking glasses and an upwardly and outwardly projecting peripheral rim 18 which extends over the rim 11 of the base plate and provides means for manually turning the carrier 16 about the bottom end of the stem 12 to successively bring the drinking glasses mounted upon the carrier into position for filling from the beverage dispenser.

The upper end 14 of the stem is provided with a flat top surface in which is provided a circular groove 19 concentric with the longitudinal center line of the stem. A tray 20 is mounted on the upper end of the stem 12 and includes a flat body 21 of circular shape having an upstanding peripheral flange 22 and having on one side a circular ridge 23 which is disposed concentrically of the body 21 and received in the groove 19 in the upper end surface of the stem 12. The body 21 is also provided in its upper surface with a circular groove 24 which is of substantially the same diameter and concentric with the ridge 23 on the bottom surface of this body. A pet cock 25 extends through the body 21 adjacent the flange 22 and may be opened to drain liquid from the space at the upper side of the body 21 within the flange 22.

An outer receptacle 26 is mounted upon the tray 20 and includes a bottom wall 27 having on its bottom surface a circular ridge 28 received in the circular groove in the upper surface of the body 21 of the tray and having in its upper surface a groove concentric with and of substantially the same diameter as the ridge 28. The outer receptacle also includes a side wall 29 of cylindrical shape joined at one end to the bottom wall 27 peripherally of the latter and a dome-shaped cover 30 mounted on the other or upper end of the side wall by means of an internally screw threaded rim 31 on the cover threaded onto the externally screw threaded upper end portion of the side wall. The cover 30 is of substantially hemispherical shape and is provided at the center of its convex surface with a suitable handle 32 for applying the cover to the side wall 29 of the outer receptacle and removing it therefrom.

Handles 33 and 34 are secured to the side wall 29 and project outwardly therefrom at substantially diametrically opposite locations near the upper or open end of the side wall for lifting the outer receptacle onto and off of the tray 20.

An inner receptacle 35 is disposed within the outer receptacle 26 with its cylindrical side wall 36 circumferentially spaced from the side wall 29 of the outer receptacle. This inner receptacle

has, at one end of its side wall, a bottom wall 37 provided on its outer surface with a circular ridge 38 received in the circular groove provided in the inner surface of the bottom wall of the outer receptacle, and a domed cover 39 of substantially hemispherical shape is mounted on the end of the side wall 36 of the inner receptacle remote from the bottom wall 37 by suitable means, such as the internally screw threaded rim 40 on the cover threaded onto an external screw thread formation on the side wall 36 at the end of the latter remote from the bottom wall 37.

A handle 41 is provided on the cover 39 substantially at the center of the convex side thereof and an air vent opening 42 is provided through the handle 41 and the wall of the cover.

A conduit 43 is threaded at one end into the side wall 36 of the inner receptacle and extends from the interior of the inner receptacle adjacent the bottom wall 37 through the side wall 26 of the outer receptacle. This conduit is provided with a manually operated, beverage dispensing valve 44 at the outer side of the outer receptacle. A cut off valve 45 is connected into the conduit 43 by screw thread connections and is disposed between the side walls of the inner and outer receptacles and an operating rod 46 for the valve 45 is detachably secured at one end to the valve by a pin and socket connection, as indicated at 47 and 48 in Figure 5, including a pin of noncircular cross sectional shape extending upwardly from the stem of the valve and constituting an extension of the latter, and a socket of the adjacent end of rod 46 having a concavity complementary in shape to the shape of the pin, and the rod 46 extends upwardly along the side wall 36 of the inner receptacle to a location somewhat above the upper end of the side wall 36. An apertured lug 49 projects outwardly from the side wall 36 near the upper end of the latter and receives the rod 46 and a handwheel 50 is provided on the upper end of the rod for operating the valve 45.

When the device is completely assembled, as illustrated in Figure 3, the beverage to be dispensed will be stored in the inner receptacle 35 and a suitable cooling medium, such as cracked ice, will be placed in the space between the side walls 36 and 29 of the inner and outer receptacles. The bottom wall 27 of the outer receptacle is provided near the side wall 26 of this receptacle with a circular series of drain openings 51, so that the water from the melting ice may drain from the outer receptacle into the tray 20 from which it may be drained through the pet cock 25.

When it is desired to use the device as a stand for supporting such articles as fruit, pastry or candy, the outer and inner receptacles may be omitted and the tray 20 used as the article supporting tray. Under these conditions, the rotatable drinking glass support will be retained and may be used to support clean drinking glasses convenient to a person selling articles from the stand.

When it is desired to use the device as a dispenser for hot beverages only, the outer receptacle 26 is omitted and the inner receptacle 35 is placed directly upon the upper side of the tray 20, the provision for chilling the beverage being thereby omitted.

When it is desired to dispense cold beverages, the entire device is assembled, as described above, so that a space for a chilling medium, such as cracked ice, is provided around the inner receptacle in which the beverage is stored.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A beverage dispenser comprising a base including a base plate of circular shape and having a marginal rim and a stem having a lower end engaged on said base plate centrally of the latter and having an upper end provided with a concentrically disposed circular groove therein, an element on the upper end of the stem formed with a circular groove, an outer receptacle mounted on said element and including a bottom wall provided on the under surface thereof with a circular ridge received in the groove in said element and in its upper surface with a circular groove disposed substantially concentrically of said bottom wall, a side wall rising from said bottom wall marginally of the latter, cover mounted on the upper end of said side wall, an inner receptacle disposed within and circumferentially spaced from said outer receptacle and including a bottom wall provided on its under surface with a circular ridge received in the groove in the bottom wall of said outer receptacle, a side wall rising from the inner receptacle bottom wall marginally of the latter, cover mounted on the upper end of the inner receptacle side wall, a conduit extending from the interior of said inner receptacle adjacent the bottom wall thereof through the side wall of said outer receptacle, and a manually operated valve on said conduit at the outer side of the side wall of said outer receptacle.

2. An article of manufacture comprising a base including a base plate having a marginal rim and a stem upstanding from said base plate at the center thereof, said stem having a flat top surface substantially parallel to said base plate and provided with a concentric circular groove, a tray mounted on the upper end of said stem and including a body portion having on one side a concentric circular ridge fitting into the groove in the upper end surface of said stem and a flange peripherally surrounding said body portion and upstanding therefrom, said body portion having a concentric circular groove in its upper surface, a liquid receptacle mounted on said tray and including a bottom wall having a concentric circular ridge thereon fitting into the groove in the upper surface of the body portion of said tray, a side wall joined at one end to said bottom wall and a cover mounted on the other end of said side wall, a conduit connected at one end to said receptacle adjacent said bottom wall and extending from said receptacle beyond the flange of said tray, and a manually operated dispensing valve on the outer end of said conduit.

3. An article of manufacture comprising a base including a base plate having a marginal rim and a stem upstanding from said base plate at the center thereof, said stem having a flat top surface substantially parallel to said base plate and provided with a concentric circular groove, a tray mounted on the upper end of said stem and including a body portion having on one side a concentric circular ridge fitting into the groove in the upper end surface of said stem and a flange peripherally surrounding said body portion

tion and upstanding therefrom, an outer receptacle mounted on said tray and including a bottom wall having a concentric circular ridge on its outer side received in the circular groove in said tray, a concentric circular groove on its inner side and a circular series of spaced apart apertures adjacent its edge, a side wall joined at one end to the edge of said bottom wall and a cover mounted on the other end of said side wall, an inner receptacle disposed within said outer receptacle and having a bottom wall provided on its outer side with a concentric circular ridge received in the groove in the inner surface of the bottom wall of said outer receptacle, a conduit extending from the interior of said inner receptacle adjacent said bottom wall through the side wall of said outer receptacle, a manually operated dispensing valve on said conduit outside of said outer receptacle, a manually operated cut off valve connected into said conduit between said inner and outer receptacles, and a pet cock mounted in the body portion of said tray adjacent said flange for draining liquid from the interior of said tray.

4. In a beverage dispenser, a base including a portion having an upper end formed with a circular groove, a tray on said upper end having a circular ridge engaged in said groove, said tray having an upper surface provided with a circular groove, an outer receptacle having a bottom having a circular ridge engaged in the tray groove and a side wall, the outer receptacle bottom having an upper side having a circular groove

25

15

20

therein, an inner receptacle positioned within said outer receptacle, and having a side wall, said inner receptacle being smaller in diameter than said outer receptacle and arranged with its side wall concentrically spaced from the outer receptacle side wall, said inner receptacle having a bottom having a circular ridge engaged in the groove in the outer receptacle bottom, and valved conduit means leading from the interior of the inner receptacle through the side walls of the inner and outer receptacles.

5. A beverage dispenser according to claim 4 wherein the bottom of the outer receptacle has a portion overlying said tray, such portion being formed with drain opening means.

6. A beverage dispenser according to claim 4 wherein the bottom of the outer receptacle has a portion overlying said tray, such portion being formed with drain opening means and said tray comprises valved drain means for draining off moisture accumulating in the tray from the outer receptacle drain opening means.
